UNITED STATES PATENT OFFICE.

WALTER C. FISH, OF LYNN, MASSACHUSETTS, ASSIGNOR TO GENERAL ELECTRIC COMPANY, A CORPORATION OF NEW YORK.

ARC-LAMP.

SPECIFICATION forming part of Letters Patent No. 738,896, dated September 15, 1903.

Application filed June 12, 1901. Serial No. 64,205. (No model.)

To all whom it may concern:

Be it known that I, WALTER C. FISH, a citizen of the United States, residing at Lynn, county of Essex, State of Massachusetts, have 5 invented certain new and useful Improvements in Arc-Lamps, of which the following is a specification.

My present invention relates to means for securing stability of operation of arc-lamps, 10 whereby the use of a steadyng resistance in series with the lamp may be either wholly discontinued or the amount of resistance largely reduced, thereby increasing the percentage of useful energy expended at the arc, and so improving the efficiency of the lamp as a whole.

In carrying my invention into practice I provide an arrangement whereby the arc-regulating mechanism responds readily to small variations of current, thereby securing 20 through the regulation of the arc itself a steadiness of current heretofore generally obtained by the use of a steadyng resistance, the employment of which is objectionable on account of the energy consumption therein.

25 The novel features which constitute my invention I have set forth more particularly in the claims appended hereto. For a detailed description of these novel features and of other elements going to make up a lamp constructed in accordance with my invention reference is to be had to the following description, taken in connection with the accompanying drawings, in which—

Figure 1 represents one embodiment of my 35 invention, and Fig. 2 a modified arrangement of circuits.

The lamp shown in Fig. 1 includes two sets of magnets, one set being arranged to act differentially with respect to the other and 40 both sets being controlled by current flowing through the arc. One set of magnets (indicated at 1) acts to produce a separation of the carbon or other electrodes 2 3, and I may therefore term the same "main" magnets 45 or magnet-coils. The other set of magnets or magnet-coils is indicated at 4 and is arranged to act in opposition to the first set of magnets, for which reason I may term the same "differential magnets." The windings 50 of these two sets of magnets 1 and 4 are shown

as connected in series with each other and with the electrodes 2 and 3 in a manner readily understood.

The main magnet coils 1 are arranged in operative relation to a U-shaped core 5, fixed 55 to a tube 6, which supports a clutch 7, acting on the upper or movable carbon 2.

In a somewhat similar manner the magnet-coils 4 are arranged in operative relation to a U-shaped magnet-core 8, secured to a downwardly-extending rod 9. The rod 9, which for the sake of lightness may be hollow, is connected to the tube 6 through a spring or springs 10. Various types of springs may be employed. In the present instance I have 65 shown two mechanically-connected bow-springs as suitable for the purpose, one of the springs being fixed to the rod or tube 9 and the other to the rod 6, the opposing ends of the springs being riveted or otherwise secured 70 together, as shown at 11 and 12. Interposed between the windings of the magnet 4 and the core 8 are placed heavy short circuits 13 14, consisting in the present case of thick tubes of copper or other good conducting material. The object of these short circuits is to shut off from the core 8 the effect of sudden variations of current in the windings 4, thereby rendering the differential-magnet system slow to respond to variations of current in the lamp.

To restrain too violent motion of the arc-regulating mechanism, I may employ a dashpot consisting of a cylinder 15, carried by upwardly-extending arms 16 and 17, fixed, as 85 shown, to the U-shaped core 8, and a cylinder, the lower end of which, 18, is carried by a yoke-piece 19, fastened to some fixed portion of the lamp—in the present instance to the magnets 4.

In order to make clear the mode of operation of the lamp, let it be supposed that a sudden fluctuation of current—as, for example, a sudden increase of current—takes place, due to any cause. The main magnet 1 then acts to 95 draw up its core 5, thereby producing a greater separation of the carbons 2 3. At the same time current increases in the same proportion through the winding of the differential magnet 4. Owing, however, to the screening ef- 100

fect of the short circuits 13 the effect of this fluctuation of current is not immediately felt by the core of the differential magnet, due to which fact the resultant action of the main 5 and differential magnets is for a moment increased by a considerably greater amount than that which would result with a slow increase of current to the same value as that momentarily existing in the magnet-coils 10 and 4. The sudden impulse thus exerted on the arc-regulating mechanism thereupon promptly separates the electrode and brings the current back to its normal value, the action being so prompt as to prevent the fluctuation of current from reaching any considerable proportions, such as would endanger the stability of the lamp and set the parts to pumping or hunting.

In case a decrease of current momentarily 20 takes place the magnetomotive force of the main coil 1 decreases correspondingly, while that of the differential coil 4 lags behind, being retarded in this case by the induced current set up in the short circuits 13 and 14. 25 The resultant differential action of the coils 1 and 4 is therefore decreased in a greater proportion than the decrease of current, thereby permitting a more prompt approach of the electrodes 2, 3, and so preventing a violent 30 fluctuation of current by checking the fluctuation in its incipiency. This action is hastened through the instrumentality of the energy stored up in the springs 10. Thus when the lifting power of the magnets 1 decreases, 35 due to decrease in current, the springs 10, which are under compression, add their tension to that of gravity, thus obtaining increased acceleration of the carbon-holding mechanism in its downward movement. The 40 tube or rod 9, attached to the magnet-core 8, receives the reactive force of the springs 10 and adjusts its position as the arc-controlling mechanism gradually moves downward as the upper carbon burns away, thereby maintaining 45 the springs 10 under substantially uniform tension whether the clutch 7 is at the feeding-point or is at the limit of its upward movement.

Fig. 2 shows an arrangement of circuits 50 whereby the retardation or lagging of the magnetic pull of the differential coils may be increased still more than is obtainable by the use merely of the short circuits 13 and 14. (Shown in Fig. 1.) In Fig. 2 the main magnet-coils are indicated in diagram at 20 and the differential coils at 21, the latter coils being shown as wound about short circuits 22 and 23 of the same character as in Fig. 1. The differential magnet-coils 21, however, instead of being placed directly in series with the main magnet-coils 20, as in Fig. 1, are placed in one of two branch circuits which carry the current flowing through the magnet-coils 20. The branch containing the coil 55 21 includes an inductance-coil 24 of considerable self-induction. The other branch contains a non-inductive resistance 25 and is

shunted about the branch including the inductance-coil 24 and the windings 21, as shown. Current is supplied by mains, (indicated conventionally at 26 and 27,) and after passing through the parts already described flows through the arc 28 and back to the supply-mains, as indicated. In the arrangement thus described it will be evident that in the 75 event of a fluctuation of current in the arc there will be a resulting subdivision of current in the two branch circuits mentioned. The non-inductive branch 25, being of very low-time constant, offers little if any retardation to the fluctuation of current in the arc. Current in the other branch circuit, which has a high-time constant, due to the presence therein of the inductance-coil 24, is prevented from rising or falling quickly due to the 80 choking action of the inductance-coil. The response of current in this branch circuit being therefore lagged behind that in the main circuit including the arc causes the magnetic effect of the differential winding 21 to lag 85 correspondingly. This effect is intensified still more by the presence of the secondary or short circuits 22 and 23 in a manner well understood in the art. Since the differential effect of the magnet or coils 21 is by the means 90 described lagged or retarded behind that of the main coils 21, it will be evident that the resultant effect of the magnet system as a whole is rendered more powerful for temporary fluctuations of current than is the case after the current becomes steady. The result is that the tendency to variation of current in the arc is powerfully checked at its inception and the progress of further variation destroyed. The 95 operation of the lamp is thus rendered stable 100 and corresponding advantages secured, as above indicated.

What I claim as new, and desire to secure by Letters Patent of the United States, is—

1. The combination of a main magnet-winding, an opposing winding in circuit with the main winding, a short-circuited conductor in operative relation to said opposing winding, and a clutch mechanism in operative relation to said windings.

2. In an electric-arc lamp, the combination of a plurality of controlling-magnets connected in series, and means for retarding the magnetic effect of one of said magnets.

3. In an electric-arc lamp, the combination of a main magnet tending to strike the arc, an opposing magnet, and means for causing the current in the winding of the opposing magnet to lag behind or be retarded with respect to the current flowing in the main 120 magnet.

4. In an electric-arc lamp, the combination of a magnet-winding, an inductance-coil in shunt with said winding, and a non-inductive shunt across said inductance-coil and 125 winding.

5. In an electric-arc lamp, the combination of means acting to separate the electrodes of the lamp, electrical means for opposing such

separation, and means for rendering the action of such opposing means more sluggish than that acting to separate the electrodes.

6. The combination of a main armature, 5 clutch mechanism carried thereby, an armature acting in opposition to the main armature, and a spring connecting said armatures.

7. The combination of a main armature, 10 clutch mechanism carried thereby, an opposing or differential armature, and a compression-spring connecting said armatures.

8. In an electric-arc lamp, the combination 15 of an arc-striking magnet, a mechanism controlled thereby, a spring for opposing motion of said mechanism, and an electrically-actuated movable device for receiving the reactive effect of said spring.

9. In an electric-arc lamp, the combination

of a magnet tending to oppose the lengthening of the arc, and means for causing the magnetic effect of said magnet to vary slower than the variation of current through the arc. 20

10. In an electric-arc lamp, the combination of a main coil and a differential coil, both connected so as to carry current flowing through the arc, and a short-circuited conductor for causing the magnetomotive force due to the current in the differential-coil to vary at a rate slower than the rate of variation of current in the main coil. 25

In witness whereof I have hereunto set my hand this 7th day of June, 1901.

WALTER C. FISH.
